OPHTHALMIC MOUNTING

Ralph W. Lake, Yreka, Calif.

Application January 2, 1943, Serial No. 471,091

4 Claims. (Cl. 88—41)

This invention relates to improvements in ophthalmic mountings and has particular reference to a novel ophthalmic mounting of the type embodying combined metallic and non-metallic parts.

One of the principal objects of the invention is to provide novel means of retaining the parts of an ophthalmic mounting of the above character in proper adjusted and aligned relation with each other.

Another object is to provide means in a mounting of the type having lens supporting rims and relatively long and slender temple supports shaped to follow substantially the upper contour shape of the rims adapted to retain said temple supports in adjusted relation with the rims and which will be substantially invisible when the parts are in position of use.

Another object is to provide anchor means adjacent the temporal ends of the relatively long and slender temple supports of the above character having a portion adapted to fit between the edge of the lens and the lens retaining groove of the rim so as to be substantially invisible and to retain the parts in desired relation with each other.

Another object is to provide anchor means of the above character for use in combination with rims formed of non-metallic expandable and contractable material whereby the said anchor means is held between the edge of the lens and the lens retaining groove of the rim by the contraction of the rim on the lens.

Another object is to provide a separable clip attachment for ophthalmic mountings of the above character for retaining long slender temple supports in adjusted position relative to the rims.

Another object is to provide anchor means for relatively long and slender temple supports of the above character adapted particularly for use with mountings having expandable and contractable lens rims which will not interfere with the free expansion and contraction of said rims and which will relatively permanently retain the parts in proper relation with each other when in position of use.

Another object is to provide a simple, efficient and compact construction of the character described whereby the parts, under normal conditions of use, will be in relatively intimate compact relation with each other and yet afford ease and simplicity of adjustment.

Other objects and advantages of the invention will become apparent from the following de-

scription taken in connection with the accompanying drawing and it will be apparent that many changes may be made in the details of construction and arrangement of parts without departing from the spirit of the invention as expressed in the accompanying claims. I, therefore, do not wish to be limited to the exact details of construction and arrangement of parts shown and described as the preferred forms only 10 have been given by way of illustration.

Referring to the drawing:

Fig. 1 is a perspective view of a mounting embodying the invention;

Fig. 2 is a top plan view of said mounting;

15 Fig. 3 is an enlarged sectional view taken as on line 3—3 of Fig. 1 and looking in the direction indicated by the arrows; and

Fig. 4 is a view generally similar to Fig. 3 of a modified form of the invention.

20 The present invention relates particularly to an ophthalmic mounting embodying a pair of lens rims 5 each having a continuous inner bevelled groove 6 adapted to receive the peripheral bevelled edge 7 of the lens 8. The lens rims 5 are provided on the nasal sides thereof with lugs 9 having rearwardly extending nose bearing members 10. The said rims 5 are connected by a bridge member having a central arch portion 11 and depending side portions 12 secured to attachment plates 13 as by soldering, welding or the like. The attachment plates are secured to the lugs 9 by suitable connecting means 14, such as pins, screws or the like, anchored to said plates and extending within the material of the body of the lugs.

35 The mounting is provided with relatively long and slender temple supports 15 preferably formed of metal so as to permit adjustment. The long and slender temple supports 15 are anchored at 27 to the bridge and attachment plate assembly as by soldering, welding or the like, and are dimensioned and proportioned so as to follow substantially the upper contour shape of the lens rims and to lie in the rear thereof, as illustrated in the drawing. The said long and slender temple supports progress outwardly to rearwardly extending end portions 16 to which temples 17 are pivotally attached as illustrated at 18. Spaced inwardly from said 40 rearwardly extending portions 16, as illustrated in Figs. 2 and 3, there is provided clip or anchor means 19 having an end portion 20 shaped to fit and be secured to the long and slender temple support as by soldering, welding or the like. The opposed end 21 of the clip or anchor 45

50

55

means 19 is bent to fit the bevelled edge 7 of the lens and to lie within the inner bevelled groove 6 of the rim. The said clip or anchor means is preferably formed of relatively thin sheet material and has an intermediate portion 22 which is adjustable by bending to control the space 23 between the support and rim. The intermediate portion, in addition to being adjustable, can be formed to different lengths so as to afford additional control of the spaced relation of the long and slender temple support 15 and the rim 5. As shown in Fig. 2, the clip or anchor means 19 is formed with a relatively wide end portion 21 fitting between the rim and lens and tapers rearwardly, as illustrated at 24, to a reduced end portion 20 which is attached to the support 15. It is to be understood that said support 15 may be raised or lowered relative to the rim by bending the clip or anchor means 19 with such bending affording adjustment to control the spaced relation of the temple support and rim. The said clip or anchor means 19 is adapted to retain the temple supports in proper adjusted relation with the rims during the use of the mounting and affords means for counteracting stresses and strains incident to the manipulation of the temples in donning or removing the spectacles as well as during wear thereof. The purpose of the long and slender temple supports is to avoid having conspicuous end-piece means for the temples adjacent the outer temporal sides of the rims and the clip or anchor means set forth above is in strict accord with the immediate concept of such a construction in that said clip or anchor means is substantially invisible when in position of use.

An additional purpose of providing long and slender temple supports in a construction of the character described is to provide a strut-like support between the temples and the bridge member whereby strain introduced through the manipulation of the temples will be transmitted to the bridge rather than to the lenses. The said long and slender temple supports are adapted to function cooperatively with the rims to provide a more rigid and durable lens supporting structure with the said rims affording peripheral protection for the lenses. The bridge, temple supports and clips are preferably formed of metal so as to permit ready adjustment thereof. The lens rims are formed of non-metallic material, such as methacrylate, cellulose acetate, cellulose nitrate or the like which have expandable and contractable characteristics whereby the rims may be formed continuous and be placed on the lenses by initially forming the lens rims larger than the diameter of the lenses and thereafter causing the said rims to shrink into binding relation with the lenses.

There is a decided problem in a construction of this nature in providing anchor or clip means adjacent the temporal ends of the temple supports in that said clip or anchor means, if attached to the rims, would be a hindrance to the expanding and contracting of the rims. This difficulty is overcome in the present invention by providing clip or anchor means of the type which is normally separate from the rims and which is adapted to be rigidly held in position by placing a portion of said means between the lens and rim and thereafter causing the rim to contract thereon, with the contracting function of the rim serving to retain the parts in rigid and positive relation with each other. It is quite apparent that such a construction readily permits

the expansion and contraction of the rims with no danger of having parts break out as might be the case if the clip or anchor means were attached to the rim. In this manner, the entire rim is free to expand or contract.

In Fig. 4 there is illustrated a slight modification of the invention where, instead of securing the clips or anchor means to the relatively long and slender temple supports, by soldering or the like, prior to assembling the temple supports with the rims, the clips or anchor means are provided with a portion 25 which may be wrapped around and clamped to the temple support 15. In this construction, the clip may be free to slide longitudinally of the temple support whereby it may be placed at any desired location relative to the rim to retain the parts in proper aligned relation with each other when the end 26 of the clip or anchor means is secured between the rim and lens.

In assembling the mounting the lenses are first edged to the proper size and shape and to a suitable bevelled edge to fit within the V-shaped groove internally of the rims. The rims 5 may be initially formed to a diameter which will permit the lenses to be placed internally thereof or the said rims may be stretched an amount sufficient to receive the lenses. This is accomplished by heating the rims and then expanding them by forcing them over a suitable tapered mandrel of the shape desired of the rims. The long and slender temple supports are adjusted to follow the upper contour shape of the rims and to lie in the rear thereof. The clip or anchor means of the type illustrated in either of Figures 3 and 4 is positioned between the lens and rim and the rim is thereafter allowed to contract on the lens. Such contraction may be hastened by subjecting the rim to a cooling treatment or it may be permitted to contract at room temperature depending upon the material used in forming the rim. The bridge member is adjusted to position the rims in proper spaced relation with each other according to the interpupillary distance between the eyes of the individual and to properly fit the nose bearing pads to the nose of the wearer. The said bridge member, when properly adjusted, supports the rim members and lenses in proper aligned relation with each other. In such a construction the long and slender temple supports have a two-point support; namely, at the end 27 which is attached to the bridge and attachment plate assembly and at the location of the clip or anchor means 19. In the final assembly it is quite apparent that the portion of the clip or anchor means lying between the lens and rim will be substantially invisible.

From the foregoing description it will be seen that simple, efficient and economical means have been provided for accomplishing all of the objects and advantages of the invention.

Having described my invention, I claim:

1. An ophthalmic mounting comprising a pair of continuous lens rims of expandable material having internal bevelled grooves adapted to receive and support lenses having peripheral bevelled edges in combination with a bridge member for supporting said lens rims in spaced relation with each other, long and slender temple supports each secured to the mounting at a point adjacent the bridge member and shaped to follow substantially the upper contour shape of the lens rims and having outer temple supporting ends to which temples are pivotally attached and relatively narrow clip members of relatively flat ma-

terial each having an end connected with one of said long and slender temple supports and each having a portion extending forwardly of said temple support and terminating in an end portion shaped to substantially conform to and to lie between the bevelled edge of the lens and the inner bevelled groove of the rim and in non-connected relation with the rim whereby the rim is free to be expanded when the lenses are secured in position of use.

2. An ophthalmic mounting embodying continuous undivided expandable lens rims for use with lenses, a bridge member for supporting said rims in spaced relation with each other and long and slender temple supports shaped to follow the upper contour shape of the rims and each secured to the mounting at a point adjacent the bridge member, clip means comprising a plurality of clip members, each having a portion connected with one of the long and slender temple supports and having a portion adapted to lie between the lens and rim in disconnected relation with said lens and rim whereby the rim will be free to be expanded and to contract and will firmly retain the clip member in position when the said lens and rim are in related position of use.

3. In an ophthalmic mounting the combination of a pair of beveled edged lenses, continuous undivided lens rims of expandable material each having an internal bevelled groove fitted to the lenses, bridge means connecting said lens rims, long and slender temple supports having their

- inner ends secured adjacent the bridge and being shaped substantially to follow the upper contour shape of the rims and terminating in temple pivotal connections and relatively narrow clip members formed of normally flat relatively thin sheet material each having an adjustable portion connected to a long and slender temple support to vary the distance between the rim and temple support and a portion in non-connected relation with the rim but shaped substantially to the shape of the bevelled edge of the lens and secured between the edge of the lens and the rim by causing the material of the rim to contract and intimately fit the contour of the lens.
4. In an ophthalmic mounting the combination of a pair of lenses, continuous undivided expandable lens rims, a bridge member supporting said rims in spaced relation with each other and long and slender temple supports shaped to follow the upper contour shape of the rims and each secured to the mounting at a point adjacent the bridge member, clip means comprising a plurality of clip members, each having a portion connected with one of the long and slender temple supports and having a portion lying between the lens and the rim in disconnected relation with said lens and rim whereby the rim, when being assembled with the lens, will be free to be expanded and to contract and will firmly retain the clip member in position when the said lenses and rims are in said related position of use.
